UNITED STATES PATENT OFFICE.

FRITZ BALZER, OF MOLINE, ILLINOIS, ASSIGNOR TO TROY LAUNDRY MACHINERY CO., LTD., OF CHICAGO, ILLINOIS, A CORPORATION OF NEW YORK.

OPERATING MECHANISM FOR WASHING MACHINES.

Application filed April 25, 1924. Serial No. 708,938.

To all whom it may concern:

Be it known that I, FRITZ BALZER, a citizen of the United States, residing at Moline, in the county of Rock Island and State of Illinois, have invented certain new and useful Improvements in Operating Mechanism for Washing Machines, of which the following is a specification.

The present invention relates to operating mechanism for washing machines.

Washing machines are commonly provided with a rotary cylinder together with mechanism for rotating said cylinder a predetermined number of revolutions in one direction, then a predetermined number of revolutions in the reverse direction, this alternation in the direction of rotation being maintained throughout the washing operation. This reversing process is usually accomplished, on belt driven machines, by the use of two loose pulleys and a tight pulley, said pulleys being served by a straight and a crossed belt. The straight and cross belts are moved by mechanism provided for the purpose in such a manner that first the one and then the other of said straight and crossed belts are moved into driving relation with the tight pulley. When the machine is at rest, both the straight and crossed belts are on the loose pulleys.

In washing machine construction the rotary cylinder is commonly mounted within an outer housing, both the rotary cylinder and the housing being provided with doors whereby access may be had from the outside of the housing to the interior of the cylinder. It is necessary, of course, in order to provide such access that the cylinder must be so spotted with reference to the housing that the cylinder door and the housing door are in registry. In order to stop the cylinder at the proper position, in devices as heretofore provided, a number of motions have been necessary on the part of the operator.

An object of the present invention is to provide washing machine control mechanism which will eliminate a large number of the motions now required on the part of the operator and which will simplify the matter of stopping the cylinder at any desired point.

A further object is to provide washing machine control mechanism in which the control is localized.

A further object is to provide washing machine control mechanism which is sturdy in construction and little liable to get out of order.

Further objects will appear as the description proceeds.

The one figure of the drawing is a perspective view of a preferred embodiment of the present invention.

The numeral 1 indicates a shaft, which may be mounted in parallel relation with the axis of a washing machine cylinder. Said shaft 1 is provided with a pinion 2 for driving the washing machine cylinder (not shown). Mounted upon the shaft 1 is certain brake mechanism, indicated by the numeral 3, which brake mechanism is operated by means of the lever 4. The details of the brake mechanism need not be illustrated or described, brake mechanisms for the purpose being well known and readily procurable in the market. Securely fastened to the shaft 1 is the pulley 5, which pulley will be referred to hereinafter as the tight pulley. Said tight pulley 5 is flanked on its two sides by the loose pulleys 6 and 7, said pulleys 6 and 7 being capable of free rotation upon shaft 1. Belts 8 and 9 are provided, which are adapted to be simultaneously shifted by mechanism which will be referred to hereinafter. When it is desired to have the shaft 1 stopped, the belts 8 and 9 will ride upon loose pulleys 6 and 7 exclusively. For rotation in one direction belt 9 will be shifted to tight pulley 5, and for rotation in the opposite direction belt 8 will be shifted to the tight pulley 5. For reasons which will be referred to hereinafter, the belt 8 has driving relation with the loose pulley 6 at all times. For this purpose the width of pulley 8 may be greater than the width of pulley 9.

Mounted adjacent to the shaft 1 is the power transmitting casing 10, which casing contains certain cam mechanism operatively connected to the loose pulley 6. Driven by the mechanism within the casing 10 is the arm 11, which arm may be provided with the arcuate lower portion 12. The portion 12 is provided with a notch 13, which will be referred to hereinafter.

The details of the mechanism within the casing 10 need not be illustrated or described, it being sufficient to state that during continuous rotation of the pulley 6 in

one direction, the arm 11 will be oscillated back and forth at certain predetermined intervals, the movement of the arm 6 from one of its extreme positions to the other being relatively rapid. The mechanism for accomplishing the oscillation of the arm 11 is well known to those skilled in the art.

The numeral 14 indicates a plate for carrying belt shifter mechanism. Said belt shifter mechanism comprises lugs 15-15, which lugs carry the strap 16 encircling the tight pulley 5. Said strap 16 is provided with a pair of belt enclosing members, one of which is illustrated, being indicated by the numeral 17. Said member 17 is shown on the drawing as being operatively associated with belt 9. It will be clear that a similar belt enclosing member, secured to the strap 16, will be operatively associated with belt 8. The plate 14 may be supported for reciprocation in any preferred way. Reciprocation of plate 14 and its associated mechanism is accomplished by means of the rod 17, which is mounted in parallel relationship with the shaft 1. Mounted upon the plate 14 is the boss 18, which provides a pivotal support for the swinging lever 19, which lever is adapted to have swinging movement in a plane normal to the axis of shaft 1 and rod 17. Said lever 19 is adapted to lodge itself within the notch 13 of arm 11, being biased to a position for such lodgment by the weight 20. Enveloping the rod 17 is the sleeve 21, which sleeve 35 is adapted to have an oscillating movement about the axis of rod 17. Said sleeve 21 is provided with the abutment member 22, which is adapted to hold lever 19 out of its biased position, that is—out of lodgment 40 with the notch 13 of the arm 11. The sleeve 21 is also provided with an arm 23 fixed thereto, which is connected with the brake arm 4 by means of the adjustable rod 24. It will be clear that rotation of sleeve 21 in 45 the direction of the arrow will result in the disengagement of lever 19 from the arm 11. Such movement will also draw down the arm 4 of the brake mechanism 3 whereby to cause said brake mechanism to perform its braking functions.

Cooperatively associated with one end of the rod 17 is the member 25, which operates through a link 26 to control the movement of a lever 27. The lever 27 is fixed to a sleeve 28, which is adapted to have an oscillating movement within the bearing 29. Fixed to the sleeve 28 is the handle box 30, which handle box is provided with the handle 31 pivoted thereto about the axis 32. It will be clear that reciprocation of the rod 17, which reciprocation is longitudinal of said rod, will communicate an oscillating movement to the sleeve 28 and the handle box 30, which oscillating movement 60 will be co-axial with the axis of sleeve 28.

Mounted within the sleeve 28 is the rod 33, which rod is connected at one of its ends to the handle 31 and at the other of its ends to the bell crank lever 34, which bell crank lever is pivoted for movement 70 about the axis 35. The bell crank lever 34 is adapted to lodge within a slot 34' formed in the lever 27. The parts of lever 27 adjacent to the slot 34' may be rounded off, as indicated by the numerals 34''—34'', 75 to facilitate the matter of locating lever 27 in such a position that slot 34' will coincide with bell crank lever 34, the reason for which will appear hereinafter. The other arm of the bell crank lever 34 is connected, 80 by means of the rod 36, to an arm 37, which arm 37 is secured to the sleeve 21.

A mode of operation of the above described embodiment of the present invention is substantially as follows: When it is desired to operate the washing machine for normal operation, that is—a predetermined number of revolutions in one direction, alternating with a predetermined number of revolutions in the reverse direction, the handle 31 will be moved to the dotted line position indicated by the numeral 38. This movement of the handle 31 will result in the movement of rod 33 and bell crank lever 34 to pull down on the rod 36. The pulling down on 95 the rod 36 will cause rotation of sleeve 21. Such rotation of sleeve 21 will move abutment member 22 out of cooperative relationship with the lever 19. Assuming that the belt 8 has been driving the loose pulley 6 and thereby communicating an oscillatory movement to the arm 11, the notch 13 will be brought into a position at which the lever 19 may lodge therein. Oscillating movement of the arm 11 will, by reason of 100 the connection between said arm 11, lever 19 and plate 12, result in the reciprocation of the belt shifting strap 16 in a direction parallel with the axis of the shaft 1. Movement of strap 16 will cause the shifting of the belts 8 and 9 whereby one or the other of said belts will be moved into cooperative relationship with the tight pulley 5 for a 105 predetermined number of revolutions of said tight pulley 5. After said predetermined 110 number of revolutions have been accomplished, the arm 11 will be moved to cause the shifting of the belts, whereby rotation of the shaft 1 is reversed. The reciprocation of the plate 14 will result in the longitudinal reciprocation of the rod 17, which, acting through the member 25, link 26 and lever 27, will oscillate the sleeve 28 to cause oscillation of the handle box 30 about the axis 115 of said sleeve 28. Oscillation of the handle box 30 will therefore continue throughout rotation of shaft 1. When it is desired to 120 stop the washing machine, the handle 31 will be grasped and moved to its full line position. This movement will result in the 125 130

raising of the rod 36, causing the sleeve 21 to rotate. This rotation of the sleeve 21 will accomplish two functions. It will cause abutment member 22 to move the lever 19 out of lodgment in the slot 18 or arm 11, whereby the cooperative relationship between the belt shifter plate 14 and rod 11 will be interrupted. Rotation of sleeve 21 in the direction of the arrow will also cause the 5 brake rod 24 to lightly apply the brake 3. In order to simplify the duties of the operator, the present invention contemplates means whereby the stopping of the washing machine cylinder at the proper point may 10 be accomplished with the exercise of a minimum of discretion on the part of said operator. The washing machine cylinder should be stopped at a predetermined point in the oscillation of the handle box 30 about 15 the axis of sleeve 28. It is not considered advisable to rely upon the operator to bring the washing machine from full speed to a dead stop at any predetermined point of said oscillation, for which reason the preliminary 20 braking above referred to is made use of. At the time that the handle 31 is moved to full line position, the handle box may be at any point in its range of oscillation, and consequently belts 8 and 9 may be at any 25 point within their range of shifting. After slowing down the washing machine cylinder by reason of the light application of the brake 3, the operator may inch the washing machine cylinder to the proper position. 30 By swinging the handle box 30 coaxially with sleeve 28, the positions of the belts 8 and 9 may be controlled as desired to control the rotation of shaft 1 which is geared to the washing machine cylinder (not shown). 35 When said washing machine cylinder is properly spotted, the handle 31 will be moved to a position such that the slot 34' is in a position to receive bell crank lever 34, after which said handle will be moved to the dotted line position indicated by the numeral 39. The rounded portions 34' adjacent to the slot 34' will facilitate the locating of lever 27 in such a position that notch 34' will engage with the bell crank lever 34. 40 Movement of the handle 31 to the full stop position indicated by the numeral 39 will result in the raising of rod 36, which produces a further rotation of sleeve 21 in the direction of the arrow. This movement will 45 cause the brake rod 34 to fully apply the brake to shaft 1, whereby the washing machine cylinder will be brought to a full stop. It will be noted that at this time, i. e., with the handle box 30 at such a point in its range 50 of oscillation that notch 34' coincides with bell crank lever 34, the belts 8 and 9 will both be on the loose pulleys, so that there will be no tendency for the washing machine cylinder to rotate. 55

By reason of the present invention a struc-

ture is provided by means of which an operator may with a minimum of skill bring a washing machine cylinder to a stop at a predetermined point in its rotation. Though a preferred embodiment of the present invention has been described in detail, it will be understood that many modifications will occur to those skilled in the art. It is intended in this patent to cover all such modifications that fall within the scope of the invention as defined by the appended claims.

What is claimed is:

1. Belt shifting mechanism comprising a pair of loose pulleys and a tight pulley, belts cooperating therewith, a shaft connected with said tight pulley, said belts being adapted selectively to drive said tight pulley in opposite directions, an oscillating member driven by one of said loose pulleys, belt engaging mechanism adapted to be engaged with or disengaged from said oscillating member, a brake for said shaft, and a unitary control for controlling said brake and for controlling the connection between said oscillating member and said belt engaging mechanism.

2. In combination, a rotary shaft, a source of power, means for controlling the rotation of said shaft from said source to produce a predetermined number of revolutions in one direction alternating with a predetermined number of revolutions in the opposite direction, means for interrupting the driving relation between said shaft and said source, a brake for said shaft, and common means for applying said brake and controlling said interrupting means.

3. In combination, a rotary shaft, a source of power, automatic means for controlling the connection between said source of power and said shaft for alternately producing rotation of said shaft in opposite directions, a brake, and unitary manually operable means for controlling the connection between said source of power and said shaft for alternately producing rotation of said shaft in opposite directions and for controlling said brake.

4. In combination, a rotary shaft, a source of power, automatic means for controlling the connection between said source and said shaft for alternately producing rotation of said shaft in opposite directions, a brake for said shaft, and manually operable means for operating said brake and for controlling the connection between said source and said shaft to control the direction of rotation of said shaft by said source independently of said automatic means.

5. In combination, a rotary shaft, a source of power, automatic means for controlling the connection between said source and said shaft for alternately producing rotation of said shaft in opposite directions, a brake

for said shaft, and manually operable means for operating said brake and for controlling the connection between said source and said shaft to control the direction of rotation of said shaft by said source independently of said automatic means, said manually operable means being provided with a member for disconnecting said automatic means.

6. In combination, a rotary shaft, a source 10 of power, automatic means for controlling the connection between said source and said shaft for alternately producing rotation of said shaft in opposite directions, a brake for said shaft, and manually operable means 15 for operating said brake and for controlling the connection between said source and said shaft to control the direction of rotation of said shaft by said source independently of said automatic means, said manually 20 operable means being provided with a member for disconnecting said automatic means, said manually operable means also including an oscillatable member responsive to the movement of said direction controlling 25 means, said oscillatable member including a member swinging in another direction and said manually operable member including means for preventing the full application 30 of said brake unless said oscillatable member is in a predetermined position.

7. In combination, a rotary shaft, a fixed pulley thereon, loose pulleys associated therewith, a pair of belts for selectively communicating movement to said fixed 35 pulley in opposite directions, belt shifter mechanism for said pulleys, automatic mechanism driven from one of said loose pulleys for controlling said belt shifter mechanism, a brake, manual means for operating said brake, said manual means also having a connection for controlling the connection between said automatic mechanism and said belt shifter mechanism, and handle means having oscillating movement 40 in response to movement of said belt shifter mechanism and having another movement in another direction, said handle means being capable of moving said belt shifter mechanism independently of said automatic 45 mechanism.

8. In combination, a rotary shaft, a pulley fixed thereto, loose pulleys associated with said tight pulley, straight and crossed belts, means for shifting said belts between said 50 loose pulleys and said tight pulley to cause reversals of rotation of said fixed pulley, automatic means for controlling the operation of said belt shifting means, brake means governing the connection between 55 said automatic means and said belt shifting mechanism, means for manually shifting said belt shifting means independently of said automatic mechanism, and a handle carried by said manual means for control-

ling said brake and for controlling said 65 governing means.

9. In combination, a rotary shaft, fixed and loose pulleys on said shaft, straight and crossed belts on said pulleys, belt shifting mechanism, automatic mechanism for moving said belt shifting mechanism, means governing the connection between said automatic mechanism and said belt shifting mechanism, an oscillatable member connected with said belt shifter mechanism and adapted to operate said belt shifting mechanism when said belt shifting mechanism is disconnected from said automatic mechanism, a handle member carried by said oscillatable member, a brake for said shaft, connections between said brake and said handle whereby said handle member may control said brake, said handle member being operable in a step-by-step movement, and interfitting means for preventing 80 the full application of said brake until said belt shifting mechanism is in a position to hold said belts free of said tight pulley.

10. In combination, belt shifter mechanism having a reciprocating movement, 90 automatic mechanism for shifting said belt shifter mechanism, a brake, a handle receptacle connected to be oscillated by said belt shifter mechanism, a handle pivoted to said receptacle, connections between said 95 handle and said brake, governing means for governing the connections between said automatic mechanisms and said belt shifter mechanism, and abutment means rendering it impossible to move said handle to full 100 braking position until said belt shifter mechanism is in a predetermined position.

11. In combination, a rotary shaft, belt shifter mechanism for governing the direction of rotation of said shaft, automatic 105 mechanism for controlling said belt shifter mechanism, means for governing the connection between said automatic means and said belt shifter mechanism, said governing means including a sleeve, a handle provided with means for communicating a movement of rotation to said sleeve, a brake connected with said sleeve, and a handle receptacle capable of oscillating movement 110 at right angles to the direction of movement of said handle, said handle receptacle being connected by means of a rod within said sleeve to said belt shifter mechanism.

12. In combination, a rotary shaft, belt shifter mechanism for governing the direction of rotation of said shaft, automatic 120 mechanism for controlling said belt shifter mechanism, means for governing the connection between said automatic means and said belt shifter mechanism, said governing means including a sleeve, a handle provided with means for communicating a movement 125 of rotation to said sleeve, a brake connected

with said sleeve, and a handle receptacle capable of oscillating movement at right angles to the direction of movement of said handle, said handle receptacle being connected by means of a rod within said sleeve to said belt shifter mechanism, said receptacle being provided with means for

preventing a full application of said brake by said handle until said belt shifter mechanism is in a predetermined position. 10

Signed at Rock Island, Illinois, this 18th day of April, 1924.

FRITZ BALZER.
